CLAIM

The ornamental design for electronic game housing, as
shown and described.

DESCRIPTION

FIG. 1 is a perspective view of an electronic game
housing showing my new design;

FIG. 2 is a front elevation thereof;

FIG. 3 is a right side elevation thereof; the left side
elevation being a mirror image thereof;

FIG. 4 is a rear elevation thereof; and,

FIG. 5 is a bottom plan view thereof.

FIG. 1**FIG. 2****FIG. 3**

FIG. 4**FIG. 5**
